(57) **CLAIM**

The ornamental design for a shroud of an aspirating spray nozzle, as shown and described.

DESCRIPTION

FIG. 1 is a right side view for a shroud of an aspirating spray nozzle;

FIG. 2 is a left side view for a shroud of an aspirating spray nozzle;

FIG. 3 is a front perspective view for a shroud of an aspirating spray nozzle;

FIG. 4 is a front perspective view 2 for a shroud of an aspirating spray nozzle;

FIG. 5 is a rear perspective view for a shroud of an aspirating spray nozzle;

FIG. 6 is a front end view for a shroud of an aspirating spray nozzle; and,

FIG. 7 is a rear end view for a shroud of an aspirating spray nozzle.

1 Claim, 7 Drawing Sheets

FIG. 1

FIG. 2
